[57] **CLAIM**

The ornamental design for a combined food product and support board therefor, as shown and described.

DESCRIPTION

FIG. 1 is a top plan view of the combined food product and support board therefor showing our new design;

FIG. 2 is an end view thereof;

FIG. 3 is an opposed end view;

FIG. 4 is a left side elevational view thereof;

FIG. 5 is a right side elevational view thereof; and,

FIG. 6 is a top plan view of a second embodiment of FIG. 1 thereof, the line patterns representing two colors, and the undisclosed sides and bottom, and specific shape of the disclosed top are the same as in the first embodiment.

It is understood that the undisclosed bottom of embodiments 1 and 2 of the claimed article is flat and plain.

1 Claim, 2 Drawing Sheets

FIG. 6
